UNITED STATES PATENT OFFICE.

SAMUEL J. SUMNER, OF CHICAGO, ILLINOIS.

COIN-ACTUATED LAMP SOCKET.

Application filed October 11, 1922. Serial No. 593,834.

This invention relates to a coin-controlled electric lamp and has for its object to provide a combined savings bank and desk lamp of such character that a coin such as a nickel must be deposited before the electric circuit to the bulb is established and will be automatically placed in the bank when the light is extinguished.

A further object is to provide a device of the character indicated in which the removal of the coin receptacle will operate to break the electric circuit and make the device inoperative.

The various novel features of the invention will appear in the detailed description taken in connection with the accompanying drawing forming part of this specification in which like reference characters indicate similar parts throughout.

Figure 1 is an elevation of the improved desk lamp and bank;

Fig. 2 is a vertical section through the same;

Fig. 3 is a plan view of the funnel mouth of the coin receptacle, and

Fig. 4 is a fragmentary bottom view illustrating means for securing the coin receptacle in the lamp casing.

In the drawings there is indicated a stand having a relatively wide hollow base 1 which is adapted to serve as a shell to contain a coin receptacle or bank 18. The base is provided with an upright extension 2 within which the coin-controlled mechanism is located and 3 indicates a reduced portion at the top of the stand within which is mounted a socket 4 of the ordinary type for receiving electric bulb 5. The portion 2 above the base 1 is provided with a slot 6 through which a coin may be inserted and 7 and 7' indicate the end walls of a coin chute, the wall 7' being somewhat lower than the wall 7 and serving as a backing for an electrical terminal 8 which is suitably insulated from the wall 7' and also supported and suitably insulated from a shelf 9 which extends inwardly over the hollow base 1. This terminal 8 is connected to a spring contact 10 which is positioned below contact 30' connected with the end of wire 17.

Arranged opposite the terminal 8 at the other side of the coin slot is another spring contact 11 comprising a spring finger which is suitably secured to an insulating support 12 and projects into the coin slot so as to intercept and support the coin which is in-

serted therein, the coin, when held between the terminals 8 and 11, serving as a conductor therebetween whereby electric current may flow through a conductor 13 which extends between the spring finger 11 and the socket 4. The spring finger 11 is connected to a pull-cord 14 by a suitably insulated connection which cord extends through an opening in the stand and serves, when drawn upon, to pull the free end of the finger terminal 11 out of the coin slot thus permitting the coin to drop into the coin receptacle 18. The return wire 15 which is insulated from but supported by the socket 4 may pass directly out of the stand, but has been shown as comprising two sections having a binding post 16 between the sections, and is ordinarily joined to the wire 17 forming a double twisted cord 31 as is usual.

The base 1 is constructed to receive a coin receptacle 18 being provided with inwardly directed annular flanges 26-27, the outermost flange 26 being broken away at suitable points to permit the passage of outwardly directed lugs 24 provided upon the coin receptacle 18 which are adapted to co-act with said flange by rotation of the receptacle to secure same in position. The receptacle 18 is provided with a funnel shaped coin guide 21 in its top, said funnel shaped guide being provided at its lower and smaller end with a cruci-form opening 22 to permit the passage of coins downwardly into the receptacle but adapted to prevent their outward passage therefrom. The receptacle 18 is further provided upon its top with a suitable insulating ring 23 which is adapted to engage spring contact 10 upon the insertion of the receptacle into base 1 and force same against contact member 30' to complete the circuit and put the device in condition for operation. A suitable slide door 19 is provided for the receptacle which may be secured as by lock 20. Spring members 28 provided adjacent the lower edge of the receptacle are adapted to contact with the upper flange 27 of the base 1 to secure the container in position and prevent movement thereof and suitable thumb pieces 32 may be provided upon its bottom to facilitate its insertion and removal in the lamp.

In operation it will be noted that with the coin receptacle 18 removed the circuit to the lamp is broken between contacts 10 and 30' as well as between contacts 11 and 8. The placing of the coin receptacle within the

base 1 closes contacts 10—30' and the device is in condition for use. The insertion of a suitable coin in slot 6 operates to bridge contacts 11 and 8 thus completing the circuit to the lamp. When it is desired to extinguish the light, pull-cord 14 is used by which spring contact finger 11 can be withdrawn from the coin chute whereupon the coin drops through the funnel shaped guide 21 and the cruci-form opening 22 into the coin receptacle. The release of the pull-cord 14 then permits the return of contact 11 into its position to repeat the process.

What I claim is:

In an electric lamp, a stand comprising a hollow base and a socket for receiving an electric lamp, a coin controlled circuit within the stand comprising a spring finger extending into a coin chute and against which a coin will rest to complete the circuit with the lamp, means exterior of the stand for pulling on the finger to allow the coin to pass, a coin receptacle adapted to be secured within the hollow base of the stand, and means whereby the withdrawal of the coin receptacle will operate to break the circuit.

In testimony whereof I affix my signature.

SAMUEL J. SUMNER.
